UNITED STATES PATENT OFFICE.

JOHN J. SCHEEL, OF DETROIT, MICHIGAN.

BURIAL VAULT AND METHOD OF SEALING THE SAME.

Application filed September 12, 1927. Serial No. 218,908.

The invention relates to improvements in burial vaults and methods of sealing the same, and has for its object the provision of a simple and efficient construction and method of this character adequately sealing the vault against the entry of moisture or water.

Another object of the invention is to provide such a vault constructed and arranged to imprison air therein under slight pressure, thereby excluding water or moisture therefrom.

Another object of the invention is to provide a burial vault construction, so constructed and arranged that the act of placing the cover in position thereon automatically and effectively seals the same against the entry of moisture or water.

Another object of the invention is to provide an improved method of procedure in sealing burial vaults whereby the same are effectively sealed against the entry of moisture or water from the outside.

Other objects will appear hereinafter.

The invention will be best understood by reference to the accompanying drawings forming part of this specification and, in which

Fig. 1 is a perspective view, with portions broken away and shown in section of a burial vault embodying the invention;

Fig. 2 an enlarged transverse section of the same, and

Fig. 3 a detail perspective sectional view illustrating the method of forming a sealed joint between the cover and body of the vault.

The preferred form of construction as illustrated in the drawings comprises the usual rectangular body 10 made of reinforced concrete and having its edges enlarged and provided with a central groove 11, as shown. The sides 12 and 13 of the groove 11 are made converging or sloping in form so that said groove becomes narrower toward its bottom, the inner side of the groove being very considerably higher than the outer side thereof, as shown. The borders 14 and 15 of the groove 11 are made outwardly sloping in form, as shown.

The cover 16 of the vault is also in usual form and made of reinforced concrete. Around its edges the cover 16 is provided with a depending sealing tongue or rib 17 to fit within the groove 11, as shown. The inner side of the tongue 17 is outwardly

sloping in form and substantially parallel to the inner side 12 of the groove 11, but the outer side 19 of said tongue is made substantially vertical for a purpose to be presently mentioned. The underside of the cover 16 at the points 20 and 21 adjacent the tongue 17 is shaped, as shown, to conform substantially to the borders 14 and 15 of the groove 11, the body of the cover 16 being transversely arched, as indicated. A suitable quantity 22 of cement or other suitable plastic sealing material is placed in the bottom of the groove 11 before the cover 16 of the vault is placed in position. Then the cover 70 of the vault is forced downwardly to cause the tongue 17 to enter the groove 11, as best shown in Fig. 2. The quantity of plastic material in the groove is preferably such that the entry of the tongue 17 into said 75 groove causes said material to flow upwardly around said tongue and over the surfaces 14 and 15, thus effecting a tight and efficient seal. The sloping inner sides of the groove and tongue tend to guide the cover 80 into proper position as do also the outwardly sloping surfaces 14 and 20. The form of the sides 13 and 19 of the groove and tongue form an upwardly and outwardly diverging space in the outer side of the groove as the 85 tongue 17 is forced into place therein, said upwardly and outwardly diverging space, and the lower height of the outer side of the groove tending to induce outward flow of any excess of cement in the groove and 90 thus tending to prevent flowing of the cement into the body of the vault proper in cause too much cement is placed in the groove at points.

By arranging the inner side of the groove 95 11 higher than the outer side thereof, should there be any defect in the seal thus effected, an automatic water trap or seal is provided against the entry of water or moisture from the outside into the vault. In placing the 100 cover in place, as soon as the lower edge of the tongue 17 enters the body of cement 22 in the bottom of the groove 11, an air seal is effected which traps or confines the air in the vault so that further depression of the 105 cover in placing the same in position slightly compresses the air in the vault and thus places said air under slight pressure. Such slight pressure also has a tendency to exclude air and moisture from the interior of 110 the vault.

While I have illustrated and described the

preferred form of construction and method of procedure for carrying my invention into effect these are capable of variation and modification without departing from the 5 spirit of the invention. I, therefore, do not wish to be limited to the precise details disclosed but desire to avail myself of such variations and modifications as fall within the scope of the appended claims.

10 I claim:

1. A construction of the class described comprising a body and a cover therefor, there being a groove in the edges of said body, the borders of said groove being outwardly sloping in form; a tongue on said cover fitting into said groove; and a seal of plastic material in said groove around said tongue.

2. A construction of the class described comprising a body and a cover therefor, there being a groove in the edges of said body, the borders of said groove being outwardly sloping in form and the inner border being higher than the outer one; a tongue on said cover fitting into said groove, the underside of said cover conforming substantially to the borders of said groove; and a seal of plastic material in said groove around said tongue.

3. A construction of the class described comprising a body and a cover therefor, the edges of said body being enlarged and provided with a central groove having downwardly converging sides, the borders of said groove being outwardly sloping in form and the inner border being higher than the outer one; a tongue on said cover fitting into said groove, the inner side of said tongue being substantially parallel to the inner side of said groove and the outer side of said tongue being substantially vertical, the underside of said cover conforming substantially to the borders of said groove; and a seal of plastic material in said groove and on the borders thereof.

4. The method of sealing burial vaults

which consists in providing a body and cover therefor, the edges of said body being provided with a central groove having its inner side higher than the outer side thereof, the borders of said groove being outwardly sloping in form and the cover being provided with a depending tongue fitting into said groove; then placing said cover in place and forcing said tongue downwardly 55 into said groove.

5. The method of sealing burial vaults which consists in providing a body and cover therefor, the edges of said body being provided with a central groove having its inner side higher than the outer side thereof, the borders of said groove being outwardly sloping in form and the cover being provided with a depending tongue fitting into said groove; then placing said cover in place and forcing said tongue downwardly 60 into said groove, to cause said plastic material to flow upwardly around said tongue and over the borders of said groove.

6. A construction of the class described comprising a body and a cover therefor, the edges of said body being provided with a central groove having downwardly inclined and converging sides, each border of said groove being outwardly sloping in form and the inner border being higher than the outer one; a tongue on said cover fitting into but somewhat smaller than said groove, the inner side of said tongue sloping outwardly and downwardly substantially parallel to the inner side of said groove and the outer side of said tongue being substantially vertical, thereby providing an inner space around said tongue having substantially parallel sides and an outer space having upwardly 75 diverging sides; and a seal of plastic material in said groove.

In testimony whereof I affix my signature at 1609 First National Bank Building, Detroit, Michigan.

JOHN J. SCHEEL.
